Office Action of Japanese Design Application No. D2010-031348, 3 pgs., mailed on Jul. 11, 2011, (Japan) containing Japan Patent Office Prior Art No. HJ20040039, "Sea & Sea," Sea and Sea Sunpack Co., Ltd., <http://www.seaandsea.co.jp/press/1223343674.html> , (Nov. 2008), which was deposited as Patent Office on Nov. 21, 2008.

Primary Examiner — Cynthia Underwood

(74) *Attorney, Agent, or Firm* — Rader, Fishman & Grauer PLLC

CLAIM

The ornamental design for a camera, as shown and described.

DESCRIPTION

FIG. 1 is a front, top, right perspective view of a first embodiment of a camera showing our new design;

FIG. 2 is a rear, top, left perspective view thereof;

FIG. 3 is a front elevational view thereof;

FIG. 4 is a rear elevational view thereof;

FIG. 5 is a left side elevational view thereof;

FIG. 6 is a right side elevational view thereof; and

FIG. 7 is a top plan view thereof.

FIG. 8 is a front, top, right perspective view of a second embodiment of a camera showing our new design;

FIG. 9 is a rear, top, left perspective view thereof;

FIG. 10 is a front elevational view thereof;

FIG. 11 is a rear elevational view thereof;

FIG. 12 is a left side elevational view thereof;

FIG. 13 is a right side elevational view thereof; and,

FIG. 14 is a top plan view thereof.

Portions in broken lines are for illustrative purpose only and

form no part of the claimed design.

1 Claim, 12 Drawing Sheets
